Primary Examiner — Kelley Donnelly(74) *Attorney, Agent, or Firm* — Lexyoume IP Meister, PLLC(57) **CLAIM**

The ornamental design for showcase frame extrusion, as shown and described.

DESCRIPTION

FIG. 1 is a top and left side perspective view of a showcase frame extrusion showing my new design;

FIG. 2 is a front elevational view thereof, a rear elevational view is mirror image;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top and right perspective view of the showcase frame extrusion shown of FIG. 1;

FIG. 8 is a top and left view of the showcase frame extrusion shown in its position of use; and,

FIG. 9 is a front sectional view of the showcase frame extrusion shown in its position of use, taken along a line 9-9 of FIG. 5.

The broken lines are for the purposes of illustrating the environment of the article only and form no part of the claimed design.
